UNITED STATES PATENT OFFICE.

GEORGE P. BUMP, OF LA CROSSE, WISCONSIN, ASSIGNOR OF ONE-HALF TO J. C. HAWKINS, OF NEWTON, IOWA.

METHOD OF FASTENING PAPER SHEETS AND THE LIKE.

1,009,644.

Specification of Letters Patent. Patented Nov. 21, 1911.

Original application filed May 14, 1909, Serial No. 495,985. Divided and this application filed February 11, 1911, Serial No. 608,153. Renewed October 24, 1911. Serial No. 656,482.

To all whom it may concern:

Be it known that I, GEORGE P. BUMP, a citizen of the United States, residing at La Crosse, Wisconsin, have invented certain new and useful Improvements in Methods of Fastening Paper Sheets and the Like, of which the following is a specification.

My present invention relates to the method of fastening paper or like sheets together, such as is disclosed in my application for Letters Patent of the United States filed May 14, 1909 #495,985, my present invention being a division of the subject matter disclosed therein.

In the accompanying drawings: Figure 1 is a plan view of two superimposed sheets with the tongue cut therefrom, and the slit cut therein in accordance with the first step in my method; Fig. 2 is a sectional view of the fastener of Fig. 1; Fig. 3 is a view similar to Fig. 2 showing the next step in the method in which the tongue is folded back and is being drawn through the slit; and Fig. 4 is a view of the completed tongue.

In carrying out my method, the superimposed paper sheets are cut to form the

tongue 1 and are slit at 2. The tongue is folded back and is then drawn through the slit, the intermediate part of the tongue being doubled up and entering the slit first 30 and this continuing until the point or end of the tongue passes through the slit and snaps or straightens out over the upper sheet. These actions are illustrated in Figs. 3 and 4.

35

I claim as my invention:

The herein described method of fastening together paper sheets or the like consisting in superimposing said sheets, cutting a tongue therefrom and cutting a slit therein, 40 folding the tongue back, then bending it toward the slit at a point intermediate of its length, and then drawing this bent portion of the tongue through the slit in advance of the end of said tongue, substantially as 45 described.

In testimony whereof, I affix my signature in presence of two witnesses.

GEORGE P. BUMP.

Witnesses:

BASIL I. PETERSON,
Otto M. SCHLABACH.
